UNITED STATES PATENT OFFICE.

LAURENCE E. TOPHAM, OF BEVERLY, MASSACHUSETTS, ASSIGNOR TO UNITED SHOE MACHINERY COMPANY, OF PATERSON, NEW JERSEY, A CORPORATION OF NEW JERSEY.

SEWING-MACHINE.

1,129,760.

Specification of Letters Patent. Patented Feb. 23, 1915.

Application filed October 25, 1911. Serial No. 656,685.

To all whom it may concern:

Be it known that I, LAURENCE E. TOPHAM, a citizen of the United States, residing at Beverly, in the county of Essex and State of Massachusetts, have invented certain new and useful Improvements in Sewing-Machines; and I do hereby declare the following to be a full, clear, and exact description of the invention, such as will enable others skilled in the art to which it appertains to make and use the same.

The present invention relates to shoe sewing machines, and more particularly to shoe sewing machines of that class which are used to stitch the outsole to the welt of a welted shoe.

The principal object of the present invention is to provide an improved mechanism, by which an outsole shoe sewing machine can be stopped in a certain and reliable manner at a predetermined point in the cycle of operations of the machine without undue shock and wear upon the parts, and by which the presser foot of the machine can be raised and held in raised position while the machine is stopped to permit the removal and insertion of work.

Another object of the invention is to provide an improved mechanism for raising the presser foot of a sewing machine from the work as the driving shaft of the machine is stopped, regardless of the particular means which is employed for stopping the machine at a predetermined point in the cycle of operations of the machine.

With the above objects in view a feature of the present invention contemplates the provision in a shoe sewing machine provided with a presser foot, of means under the control of the operator for slowing down the driving shaft of the machine, for then driving the shaft at a predetermined low speed, and then stopping the machine while it is being driven at this low speed at a certain predetermined point in the cycle of operations and causing the presser foot to be raised from the work as the machine is stopped.

To enable the speed of the driving shaft to be slowed down and driven at a predetermined low speed before the machine is stopped, the present invention contemplates the provision of high and low speed driving mechanisms for the driving shaft of the machine, the high speed driving mechanism be-

ing in operation during the sewing of the seam and the slow speed mechanism being thrown into operation just before the machine is to be stopped.

In the preferred form of the invention the slow speed driving mechanism comprises a friction clutch, one member of which is constantly rotated at a low speed and is loose on the driving shaft, while the other member is mounted to rotate with the driving shaft but is capable of moving longitudinally thereon so as to clutch the shaft to the rotating member of the clutch. Preferably the clutch members are provided with friction surfaces, which surfaces first act as a brake to slow down the speed of rotation of the driving shaft, and then act to drive the shaft at a predetermined low speed. In the construction hereinafter specifically described as embodying the preferred form of this feature of the invention, means are provided for throwing the slow speed clutch into operation at a predetermined time in the cycle of operations of the machine, in order that a sufficient length of time may be provided before the clutch is thrown out and the driving shaft stopped for the driving shaft to be slowed down and be driven at a predetermined low speed by the slow speed clutch.

The means for throwing the slow speed clutch into operation is preferably automatic in its action and is under the control of the operator, means under the control of the operator being provided whereby the high speed driving mechanism can be thrown out of operation and the mechanism for throwing in the low speed clutch rendered active. The means for throwing the high speed driving mechanism out of operation and for throwing the low speed clutch into operation constitutes a means under the control of the operator for shifting from the high to the low speed driving mechanism at the end of the sewing operation when the driving shaft of the machine is to be stopped.

In connection with the high and low speed driving mechanism above referred to, mechanism is provided by which the presser foot is raised from the work as the machine is stopped. This mechanism is normally inoperative during the sewing of the seam but acts automatically to lift the presser foot from the work after the slow speed mecha-

nism has been thrown into operation so that the presser foot is automatically raised from the work during the final rotation of the driving shaft and is held in raised position 5 after the driving shaft comes to rest. This mechanism for lifting the presser foot is under the control of the operator and in the preferred form of the invention the control is secured by connection to the devices 10 which are utilized in controlling the mechanism for shifting from the high to the low speed driving mechanism.

In its broader aspects, the present invention contemplates the provision of a low 15 speed driving mechanism which will rotate the driving shaft in either direction. It is preferred, however, to arrange the low speed driving mechanism so that it rotates the driving shaft in the same direction as the 20 high speed mechanism, as thereby the rotation of the driving shaft does not have to be reversed and the shaft can be slowed down to a given speed and then stopped with less jar and less wear on the parts.

25 Those features of the present invention which relate to the presser foot lifting mechanism regardless of the particular kind of driving and stopping mechanism employed in the machine, comprise certain 30 novel constructions and arrangements of parts hereinafter described and claimed, the advantages of which will be obvious to those skilled in the art from the specific description 35 of the illustrated embodiment of the invention.

The several features of the present invention will be clearly understood from an inspection of the accompanying drawings, in which:—

40 Figure 1 is a view in side elevation of an outsole shoe sewing machine embodying the same in their preferred form; Fig. 2 is a plan view partly in section of a portion of the machine illustrating the low speed driving mechanism, the mechanism for shifting from the high to the low speed driving mechanism, and mechanism for raising the presser foot; Fig. 3 is a sectional view taken on the line 3—3 of Fig. 2 illustrating the mechanisms shown in Fig. 2 and also the tension device and the connections through which 45 the tension on the thread is released simultaneously with the raising of the presser foot; Fig. 4 is a vertical sectional view 50 taken on a plane passing through the driving shaft; Fig. 5 is a sectional view taken on the line 5—5 of Fig. 2 illustrating the mechanisms shown in Fig. 2 and also the presser foot and the parts of the machine associated 55 therewith; Fig. 6 is a sectional view taken on the line 6—6 of Fig. 2; Fig. 7 is a detail view in rear elevation of a portion of the 60 presser foot lifting mechanism.

The outsole shoe sewing machine illustrated in the drawings is the curved hook

needle lock stitch machine fully illustrated and described in the application of Fred Ashworth, Serial No. 585,116, filed October 3, 1910 and British Patent No. 23,478 of 1910, and accordingly so much only of the machine has been illustrated in the drawings of the present application to indicate the connection of the present invention therewith.

The work support of the machine is indicated at 1, the awl at 2, the needle at 3 and the presser foot at 4. The presser foot is mounted upon the presser foot lever 5, the lower end of which is connected by a link 6 to the mechanism by which the presser 75 foot is actuated automatically during the sewing operation. As is fully described in the Ashworth application and British patent above referred to, the presser foot during each cycle of operations of the machine 80 is allowed to rest lightly on the work, is forced positively down against the work, is locked in its depressed position and is then unlocked and raised from the work, these 85 movements of the presser foot being produced by the automatic presser foot mechanism acting through the link 6. A lever 90 90 is pivotally mounted on the presser foot lever 5 as in the machine of the Ashworth application, and acts when its upper end is moved toward the rear of the machine to unlock and raise the presser foot. This lever is connected, as in the Ashworth machine, by a link 8 to an arm 9 mounted on a stud 10 at the rear of the machine. The 95 tension device illustrated in Fig. 3 is the same as the tension device of the Ashworth machine and comprises intermeshing gear wheels over and between which the needle thread passes. The tension release lever of 100 this tension device is indicated at 11 and is connected, as in the Ashworth machine, by means of a flexible cord 12 to the horizontal arm of the bell crank 13 pivoted at 14 upon the frame of the machine below the arm 9. The cord 12 passes through a sheath 15 and the arrangement is such that when the bell 105 crank 13 is rocked in a direction to raise the horizontal arm of the bell crank, the tension release lever 11 is actuated to relieve the tension on the thread.

110 During the sewing operation, the machine is driven through a belt pulley 13' secured to the end of the main driving shaft and connected by a driving belt 16 with a pulley 17 mounted in the base of the machine. The pulley 17 is connected through bevel gears 18 with a sleeve 19 mounted on the counter shaft 20 and carrying one member 21 of the main driving clutch. The counter shaft carries the other member 22 of the clutch and also carries the driving pulley 23', through which motion is imparted to the shaft. The engagement of the members 120 of the driving clutch is controlled through 125 130

a treadle 23 connected with the clutch operating wedge 24. When the treadle is depressed, the members of the driving clutch are forced into engagement and the machine is driven at a speed depending upon the pressure which the operator applies to the treadle. When the treadle is released, the clutch members are disengaged, thus disconnecting the driving shaft of the machine from the counter shaft. The upward movement of the treadle when it is released also throws into operation the mechanism by which the driving shaft is driven at a low speed and by which the shaft is stopped at a predetermined point in the cycle of operations. The slow speed driving mechanism comprises a forwardly driven friction clutch consisting of the clutch members 25 and 26. The clutch member 25 is formed on a spiral gear 27 which is loosely mounted on the driving shaft 28 and is driven during the sewing operation by a spiral pinion 29 secured to a shaft 30. The shaft 30 is continuously driven from the driving pulley 23' through a belt 31 passing over a pulley formed on the hub of the pulley 23' and over a pulley 32 secured to the shaft 30. The other member 26 of the clutch is formed on a flange projecting from a sleeve 33 which is loosely mounted upon the driving shaft 28. The sleeve 33 is free to slide longitudinally on the shaft but is connected to rotate with the shaft by means of a block 34 secured to the pulley 15' and arranged between lugs 35 projecting radially from the sleeve 33. The sleeve is held normally in position with the clutch members out of engagement by a spring 36 arranged in a recess in the block 34 and interposed between the bottom of the recess and the head of a bolt which carries a plate 37 engaging the lug 35. The normal position of the clutch sleeve is determined by an adjustable stop screw 38 which may be adjusted to maintain the clutch sleeve in proper relation to the clutch member.

When the clutch members 25 and 26 are engaged, they act as a friction brake to absorb the energy due to the momentum of the driving shaft until the shaft is rotating at the same speed as the clutch member 25, after which the driving shaft is driven forward at a predetermined low speed by the clutch until the clutch is disengaged, when the shaft is brought to rest at a predetermined point in the cycle of operations of the machine.

To enable the slow speed clutch to be thrown into operation at a predetermined time in the cycle of operations of the machine so that the driving shaft may be surely slowed down to the speed of the low speed clutch before the shaft is stopped, mechanism is provided comprising a timing cam 39 consisting of a cam groove formed in the

sleeve 33 and engaged by a roll on one arm of a bell crank lever 40. The other end of the bell crank lever is provided with a hole 42 adapted to receive a locking pin 43 which is normally held out of engagement with the lever so that during the normal running of the machine the lever is oscillated idly by the cam. The locking pin is mounted in the end of a slide 44 which is held in normal position by a spring 45. The spring surrounds a bolt 46 extending from the rear end of the slide and is interposed between a shoulder on the slide and the inner end of an adjustable screw threaded sleeve 47. The bolt 46 carries a nut 48 which engages the outer end of the sleeve and holds the spring under compression. By adjusting the nut, the compression of the spring may be varied and by adjusting the sleeve 47 the slide may be adjusted to bring the locking pin into proper register with the hole in the end of the lever 40. The locking pin is forced in a direction to engage it with the bell crank lever by a spring 49 and in order that the mechanism for throwing the slow speed clutch into operation may be under the control of the operator, the lower end of the pin is connected with the treadle 23 so that the pin is held down out of engagement with the bell crank lever so long as the treadle is depressed and the main driving clutch is acting to drive the machine. The latch 50 is also connected with the lower end of the locking pin and is arranged to engage a shoulder 51 on the slide 44 and hold the locking pin in its lower position until the treadle has been raised sufficiently to allow the locking pin to engage the bell crank lever. The latch 50 is pivotally mounted upon a block 52 secured to the lower end of the locking pin and is provided below its pivot with a horizontal portion which is acted upon by a spring 53, the tendency of which is to force the latch into engagement with the end of the slide 44. While the machine is at rest, the pin 43 is in its raised position in engagement with the bell crank lever 40. At this time, the latch 50 is held out of engagement with the slide 44 in the position indicated in Fig. 6 by means of an arm 54 pivoted on the machine frame and extending underneath the horizontal portion of the latch. The arm 54 is connected by a link 55 to a block 56 secured to the rod 57 which connects the locking pin 43 with the treadle 23. The rod 57 is connected to the locking pin 43 by a pin and slot connection indicated at 58, the slot being formed in the upper end of the rod and the pin being mounted in the block 52 at the lower end of the locking pin. With this construction, a certain amount of lost motion is provided between the rod 57 and the locking pin so that when the treadle is depressed and the rod 57 lowered, the pin at first remains sta-

tionary while the arm 54 is depressed so as to permit the latch 50 to spring into engagement with the end of the slide 44. Continued downward movement of the rod 57 depresses the pin 43 out of engagement with the lever 40, and as the latch 50 is depressed with the pin, the latch engages underneath the shoulder 51. When the treadle 23 is released, the latch 50 prevents the upward movement of the locking pin until the arm 54 strikes the horizontal portion of the latch and removes the latch from beneath the shoulder 51. When this takes place, the spring 49 forces the pin upward against the under side of the bell crank lever 40, and when the hole in the lever registers with the pin, the pin snaps up into the hole, thus connecting the lever with the slide 44.

The cam 39 is so timed that the hole in the end of the bell crank lever is brought into position to register with the locking pin at the proper time in the cycle of operations of the stitch forming mechanism. When the pin is engaged with the bell crank lever, the lever is held from movement about its pivot and the cam 39 acting on the roll carried by the lever, shifts the clutch sleeve 33 to bring the members of the slow speed clutch into engagement. When the lever and the slide 44 are locked together by the locking pin, the movement of the lever is resisted by the spring 45 and the force with which the members of the friction clutch are pressed together will depend upon the tension of the spring. This may be adjusted to secure the desired braking effect between the members of the friction clutch so that the speed of rotation of the shaft will be slowed down and the shaft be driven at the same speed as the slow speed clutch before the shaft is disconnected from the clutch and brought to rest. After the speed of rotation of the shaft has been slowed down, the continued rotation of the shaft by the slow speed clutch causes the cam 39 to disengage the clutch members so that the shaft is disconnected from all driving mechanism and is brought to rest.

The presser foot lifting mechanism illustrated in the drawings comprises a lever 59 arranged to be engaged by a cam 60 driven from the driving shaft of the machine. The lever 59 is mounted upon a sleeve 61 so that when actuated by the cam it moves in a plane at right angles to the axis of the cam shaft. The sleeve 61 is provided with an upwardly projecting arm 62 which is connected by means of a link 63 to the upper end of the bell crank lever 13. A pin 64 projects from the upper end of the bell crank 13 and is arranged to engage a stop screw 65 in an arm 66 projecting from the hub of the arm 9 which is connected to the presser foot lifting lever 7 as hereinbefore described. An actuation of the lever 59 by the cam 60 through the connections above described swings the upper end of the lever 7 toward the rear of the machine and raises the presser foot. This takes place during the final rotation of the driving shaft as the machine is brought to rest. During the normal operation of the machine in sewing a seam the lever 59 is out of operative engagement with the cam 60 so that the lever remains idle. Just before the machine is stopped, however, the lever 59 is moved into the path of the cam 60 and as the machine comes to rest the lever rides up on the raised portion of the cam and the presser foot is lifted from the work. To enable the lever 59 to be moved into and out of operative relation with the cam 60, the lever 80 is pivotally connected to the sleeve 61 by a pivot 67 arranged at right angles to the axis of the sleeve. At its lower end and at the rear of the sleeve 61 the lever 59 is provided with a horizontally extending portion 68 and the free end of this portion 68 is offset and provided with a stud 69 substantially in alignment with the axis of the sleeve 61. The stud 69 is engaged by the forward end of a lever 70, the rear end of which is connected by a link 71 to the locking pin 43, the construction being such that a downward movement of the locking pin moves the lever 59 about its pivot 67 so that its upper end is at one side of the cam 60 and out of operative relation thereto. While the machine is running the pin 43 is held depressed and consequently the mechanism for raising the presser foot is inoperative. During the operation of stopping the machine, however, the pin 43 is raised into its highest position and at this time the lever 70 is moved in a direction to allow the lever 59 to be swung about a pivot 67 into the path of the cam 60. This return movement of the lever 59 is produced by means of the spring 72 connected to the horizontal portion 68 of the lever. The operative relation of the lever 59 with the arm 62 is maintained and the strain on the pivot pin 67 when the lever 59 is actuated by the cam 60 is relieved by a projection 73 on the arm 62 arranged to bear against the rear side of the lever 59. The axial arrangement of the stud 69 with relation to the sleeve 61 maintains the stud at all times in operative relation with the lever 70 since the stud is not displaced with relation to the lever when the presser foot lifting mechanism is actuated by the cam 60.

It is often desirable for the operator to drop the presser foot upon the work before starting the machine. This result is secured in the construction illustrated in the drawings by arranging the connections between the pin 43 and the lever 59 so that the first portion of the downward movement of the pin moves the lever 59 out of operative relation with the cam, this movement of the lever taking place before the locking pin is completely withdrawn from the bell crank 40.

In the construction illustrated in the drawings there is a certain amount of lost motion in the connection between the link 71 and the pin 43. These connections consist of a slot 74 formed in the upper end of the link 71 and a pin 75 projecting from the block 52 at the lower end of the pin through the slot 74. This lost motion between the link 71 and the pin 43 allows the pin to move upwardly into engagement with the bell crank 40 while the lever 59 still remains out of operative relation with the cam 60. To hold the lever 59 out of operative relation with the cam 60 until the pin 43 has securely engaged the bell crank lever 40, a spring latch 76 is provided mounted upon the upper end of the link 71 and arranged to engage beneath the projection 77 secured to the slide 44. While the machine is running the pin 43 is in its lowered position and the latch 76 is beneath and in line with the projection 77. When the treadle is released to stop the machine, the upward movement of the link 71 is prevented by the engagement 25 of the latch 76 with the under surface of the projection 77. The latch remains in engagement with the projection until the pin 43 snaps into the hole 42 in the lever 40. When this occurs the action of the cam 39 in 30 throwing in the low speed clutch moves the slide 44 slightly to the left, as viewed in Fig. 6, against the tension of the spring 45. This movement of the slide 44 acting on the link 71 through the pin-and-slot connection 35 74—75 swings the link about its pivotal connection with the lever 70 and moves the latch 76 out of engagement with the projection 77, and allows the link 71 to rise and the lever 59 of the presser foot lifting mechanism to be moved into operative relation 40 with its cam 60. The mechanism for lifting the presser foot as the machine is stopped is therefore controlled in its operation by the mechanism which throws in the low speed driving mechanism. In the construction illustrated in the drawings the lever 59 and cam 60 in addition to forming a 45 part of the presser foot raising mechanism also act as a brake and positive stop to insure the stopping of the driving shaft at a predetermined point in the cycle of operations of the machine the lever pressing against the cam acting as a brake and the shoulder on the cam acting as a positive stop. 50 As has already been described, the lever 59 is moved out of engagement with the cam 60 before the main driving clutch is thrown into operation so that these parts offer no resistance to the starting of the machine. 55 The mechanism above described for raising the presser foot at the completion of the sewing operation also oscillates the bell crank 13 and through the connecting cord 12 and tension release lever 11 releases the

tension on the thread simultaneously with the raising of the presser foot. When the machine comes to rest therefore, the work is released by the presser foot and the thread is released by the tension so that the parts of the machine offer no obstruction to the immediate removal of the work.

The nature and scope of the several features of the invention having been indicated and the preferred embodiment of the several features of the invention having been described, what is claimed is:

1. A shoe sewing machine, having, in combination, stitch forming devices, high and low speed driving mechanisms therefor, a presser foot, means under the control of the operator for throwing the low speed driving mechanism into operation at a certain predetermined time in the operation of the machine, means for stopping the machine while it is being driven at a predetermined uniform speed by the low speed mechanism, and mechanism normally inoperative during the sewing of a seam operating automatically to lift the presser foot from the work as the machine is stopped.

2. A shoe sewing machine, having, in combination, stitch forming mechanism, high and low speed driving mechanism therefor, a presser foot, means under the control of the operator automatically to shift to the low speed driving mechanism, means for stopping the machine while it is being driven by said low speed mechanism, and mechanism for lifting the presser foot thrown into operation by said shifting means.

3. A shoe sewing machine, having, in combination, stitch forming devices, a high speed driving mechanism therefor, a low speed driving mechanism therefor arranged to drive the machine in the same direction as the high speed mechanism, a presser foot, means under the control of the operator for throwing the low speed driving mechanism into operation at a certain predetermined time in the operation of the machine, means for stopping the machine while it is being driven at a predetermined uniform speed by said low speed mechanism, and mechanism normally inoperative during the sewing of the seam operating automatically to lift the presser foot from the work as the machine is stopped.

4. A shoe sewing machine, having, in combination, stitch forming devices, a driving shaft and suitable connections between said shaft and the stitch forming devices, a presser foot, means operating automatically to lock and unlock the presser foot during each cycle of operations of the stitch forming devices, means under the control of the operator for stopping the driving shaft at a certain predetermined point in the cycle of operations, and mechanism

6
mally inoperative during the sewing of the seam operating automatically during the forward rotation of the driving shaft to unlock the presser foot and lift the presser 5 foot from the work as the machine is stopped.

5. A shoe sewing machine, having, in combination, stitch forming devices, a driving shaft and suitable connections between 10 said shaft and the stitch forming devices, a presser foot, driving mechanism including a starting and stopping treadle, a low speed clutch comprising a friction clutch member connected to rotate with the drive 15 shaft, a cam driven by the clutch member, an actuating lever operated by the cam, a locking pin operated by the treadle for rendering the lever and cam active to shift the clutch member when the treadle is actuated 20 to stop the machine, and presser foot lifting mechanism controlled by said locking pin operating automatically to lift the presser foot from the work as the machine is stopped.

25 6. A shoe sewing machine, having, in combination, stitch forming mechanism, high and low speed driving mechanisms therefor, a presser foot, shifting mechanism operating automatically when thrown into 30 operation to shift to the low speed driving mechanism, means for stopping the machine while it is being driven by said low speed mechanism at a predetermined uniform speed, presser foot lifting mechanism normally inoperative during the sewing of the 35 seam, and means under the control of the

operator for rendering said shifting and presser foot lifting mechanisms active.

7. A shoe sewing machine, having, in combination, stitch forming devices, high 40 and low speed driving mechanisms therefor, a presser foot, means for stopping the machine while it is being driven at a pre-determined uniform speed by the low speed mechanism, presser foot lifting mechanism 45 normally inoperative during the sewing of the seam, and means under the control of the operator for shifting from the high speed to the low speed mechanism and for rendering the presser foot lifting mechanism operative to lift the presser foot from the work as the machine is stopped.

8. A shoe sewing machine, having, in combination, stitch forming devices, a high speed driving mechanism therefor, a low 55 speed driving mechanism therefor arranged to drive the machine in the same direction as the high speed mechanism, a presser foot, means for stopping the machine while it is being driven by said low speed mechanism, 60 presser foot lifting mechanism normally inoperative during the sewing of the same, and means under the control of the operator for shifting to the low speed mechanism and for rendering the presser foot lifting 65 mechanism operative to raise the presser foot from the work as the machine is stopped.

Copies of this patent may be obtained for five cents each, by addressing the "Commissioner of Patents,
Washington, D. C."

It is hereby certified that in Letters Patent No. 1,129,760, granted February 23, 1915, upon the application of Laurence E. Topham, of Beverly, Massachusetts, for an improvement in "Sewing-Machines," errors appear in the printed specification requiring correction as follows: Page 5, line 93, for the word "mechanism" read *mechanisms*; same page, line 112, strike out the words "at a predetermined uniform speed"; page 6, line 62, for the word "same" read *seam*; and that the said Letters Patent should be read with these corrections therein that the same may conform to the record of the case in the Patent Office.

Signed and sealed this 30th day of March, A. D., 1915.

[SEAL.]

J. T. NEWTON,

Acting Commissioner of Patents.
